UNITED STATES PATENT OFFICE.

MORRIS WETZLER, OF NEW YORK, N. Y.

DESIGN FOR A CUFF-BUTTON.

SPECIFICATION forming part of Design No. 35,440, dated December 17, 1901.

Application filed August 9, 1901. Serial No. 71,427. Term of patent 3½ years.

To all whom it may concern:

Be it known that I, MORRIS WETZLER, a citizen of the United States, residing at 157 East Fifty-first street, in the city of New York, State of New York, have invented and produced a new and original Design for a Cuff-Button, of which the following is a specification, reference being had to the accompanying drawings, forming part thereof.

Figure 1 is a top plan view of my design for a cuff-button. Fig. 2 is a side elevation of the same.

The leading or material feature consists of the shape and configuration of the article made the subject of illustration and description.

The design for a cuff-button consists of a

hook portion *a*, from which extend two diverging arms *b c*, terminating in eyes *d d*, attached between the diverging arms *b c*, and 20 extending downwardly to terminate in a circular plate *f* is a pin *e*. The circular plate *f* is notched at *g*.

What I claim, and desire to secure by Letters Patent, is—

The design for a cuff-button as herein shown and described.

In testimony whereof I have signed my name to this specification in the presence of two subscribing witnesses.

MORRIS WETZLER.

Witnesses:

MORITZ EINSTEIN,
MERIE EINSTEIN.
